WOVEN ELASTIC FABRIC

Louis De Roon, Ridgewood, N. J., assignor to Blue Bird Silk Mfg. Co., Inc., New York, N. Y., a corporation of New Jersey

Application October 27, 1938, Serial No. 237,268

6 Claims. (Cl. 139—419)

This invention relates to woven fabrics and more particularly to woven fabrics which are elastic and which are intended primarily for use in wearing apparel. More specifically, the fabrics of the present invention as hereinafter described are especially suitable for use as the fabrics of bathing suits.

Heretofore, it has been very difficult, if not impossible, to produce woven elastic fabrics which are characterized by softness, suppleness, and drapability and which also possess a proper degree of firmness of the weave, that is a weave of such character as to provide high resistance to slippage of the warp and weft threads and to securely hold stitching when parts of the fabric are stitched together in producing a garment or other article of wearing apparel or for other purposes. One object of the present invention is to produce a woven elastic fabric which is soft or supple and which is also characterized by the substantial firmness thereof.

As heretofore constructed, woven elastic fabrics have varied in appearance or in other words have lacked uniformity of appearance in the same piece, especially in elastic fabrics which are soft or supple. I attribute this defect to the fact that the elastic or rubber threads utilized in producing woven elastic fabrics are in themselves not uniform with respect to different threads and even with respect to different portions of the same threads, and I have discovered that this defect can be obviated by weaving the fabric in such manner as to provide a multiplicity of points of resistance to the full contraction of the elastic threads, that is the return of the elastic threads from their tensioned and stretched condition in which they are woven to their contracted condition in the finished fabric when they are released from extraneous tension. In the fabrics of the present invention, the elastic threads in the finished fabric are in slightly tensioned and slightly stretched condition and are held in that condition by a multiplicity of points of resistance introduced in the fabric by weaving the same in accordance with the present invention. More specifically, the multiplicity of points of resistance to the full contraction of the elastic threads is provided in accordance with the present invention by arranging some of the warp threads in crossed relation with others of the warp threads, said warp threads being in engagement with each other at the crossings and thereby providing the proper amount of resistance necessary to prevent the full contraction of the elastic threads, or in other words to hold the

elastic threads in slightly tensioned condition in the finished fabric. This constitutes another object of the invention and from one point of view may be considered as ancillary to the above stated object of the invention.

The nature and character of fabrics of the present invention will be more fully understood from the following description considered with reference to the accompanying drawings.

In the drawings:

Fig. 1 is a plan view, on an enlarged scale, of a piece of fabric embodying the present invention;

Fig. 2 is a diagram of the weave of the fabric illustrated in Fig. 1;

Fig. 3 is a view similar to Fig. 1 showing a fabric which is somewhat different in appearance from the fabric shown in Fig. 1;

Fig. 4 is a diagram of the weave of the fabric illustrated in Fig. 3;

Referring now to the drawings in detail, the fabric 10 embodying the present invention comprises groups 12 of inelastic warp threads and groups 14 of weft threads, some of which are elastic and others of which are inelastic. Referring to Fig. 2 of the drawings which is a diagrammatic view of the weave of the fabric, it will be observed that the warp threads are arranged in groups and that some of said warp threads of each group cross the other warp threads at a plurality of points along each of a plurality of lines spaced from each other in the direction of the warp of the fabric and extending weft-wise between the groups 14 of the weft threads. Thus, as clearly shown in Fig. 2, the warp threads 12a cross the warp threads 12b at a plurality of points along each of a plurality of lines running weft-wise between the adjacent weft threads 16 of two groups 14 of said weft threads. Further it will be observed that said warp threads 12a and 12b are interwoven with weft threads of each group 14, preferably in such manner that some of said warp threads float over all of the weft threads of the group while others of said warp threads float over several but not all of the weft threads of the same group. By thus floating the warp threads over several of the weft threads in each group, the fabric has improved suppleness or softness.

The groups 14 of weft threads comprise inelastic threads 16 and elastic threads 18. Said elastic threads 18 may be of any of the types of elastic threads which are readily available on the market and which, customarily, are composed of filaments of rubber covered with textile yarn.

The other weft threads as well as the warp threads may be composed of any suitable textile material such as cotton, wool, silk or rayon, silk or rayon being preferred. It will be understood that in weaving the fabric, the elastic threads 18 are elongated or stretched and under tension and in that condition are, together with the other weft threads 16, interwoven with the warp threads 12a and 12b. For producing the crossings in the threads 12a and 12b of the warp threads 12, there is preferably utilized in the loom a leno or doup by means of which said warp threads are crossed at regular intervals as described above and as illustrated in the drawings. It will be understood further that as the fabric comes off the loom the extraneous tension on the weft threads, including the elastic threads 18, is removed with the result that the fabric contracts in width or weft-wise to the desired size of the fabric in the finished state thereof. As previously explained, however, the elastic threads 18 are not fully contracted but are maintained by the weave of the fabric and more particularly by the multiplicity of the crossings of the warp threads, in slightly stretched and slightly tensioned condition. It will be understood that while in Fig. 2 the crossings of the warp threads are shown spaced from each other and while the adjacent weft threads 16 of the groups 14 of the weft threads are shown spaced from each other, this is only for the sake of clearness of illustration, and that in the finished fabric, on the contrary, the crossings of the warp threads in the same weft-wise line are close to each other, and the groups of weft threads lie close to each other, with the result that only very small openings are present in each weft-wise line of crossings in the warp threads in the finished fabric and that said openings are barely discernible unless the fabric is held up to the light, in which case said openings between the crossings are somewhat more plainly visible. The fabric as thus produced has a high degree of softness or suppleness and yet is of uniform appearance and is characterized by substantial firmness in that it is well adapted to securely hold stitching and to resist slippage between warp and weft threads. The fabric is further characterized by the presence of a short pile on the face of the fabric produced by short loops formed in the inelastic weft threads 16 when the elastic threads 18 are in their contracted condition in the finished fabric. The fabric has a ribbed appearance in the weft.

As indicated above, the fabric may comprise various yarns in the warp and in the weft, and the size and character of the threads of the warp and the weft may vary. However, describing fabric 10 more specifically as the same has been produced in accordance with the present invention, said fabric comprises in the warp a 20 reed weave and four ends of 3-ply 100 denier Bemberg yarn of approximately 12 turns per inch, to each dent of the reed. In the filling there are 64 picks per inch of 60/2 cotton and of T-9-3 Lastex, the filling arrangement as shown in Fig. 2 including in succession 1 pick of cotton, 1 pick of Lastex (or any other suitable elastic thread), 2 picks of cotton, 1 pick of Lastex, and 2 picks of cotton, the last mentioned 2 picks being arranged one on each side of an intermediate weft-wise line of crossings of the warp threads. The fabric is approximately 50 inches in the reed and approximately 20 inches after it is removed from the loom and completely finished pursuant to the

usual methods of producing finished woven fabrics. It will be understood that the width of the fabric may vary, for example, it may be within the range of about 45 to 55 inches in the reed and about 22 to 34 inches when completely finished.

In the form of the invention illustrated in Figs. 3 and 4, the weave of the fabric 20 is, as illustrated in Fig. 4, somewhat different from the weave of the fabric 10 illustrated in Figs. 1 and 2, although it will be observed by referring to Fig. 4 that the fabric 20 includes warp threads which cross each other at a plurality of points along each of a plurality of lines spaced from each other in the direction of the warp of the fabric and extending weft-wise between adjacent weft threads. Thus as here shown, the warp threads 22 are arranged in groups and that certain of the warp threads of one group cross others of the warp threads of the group and are interwoven with the weft threads of the several groups 24. More specifically as clearly shown in Fig. 4, the warp threads 22a cross the warp threads 22b at a plurality of points along each of a plurality of lines extending weft-wise of the fabric between groups 24 of weft threads and spaced from each other warp-wise of the fabric. In each group 24 of weft threads there are inelastic threads 26 and elastic threads 28. The manner in which the warp threads are interwoven with the weft threads of each group is clearly illustrated in Fig. 4 and it will be observed that some of the warp threads float over all of the weft threads of one group, while other warp threads are more tightly interwoven with weft threads of the same group.

The materials of which the warp and weft threads of fabric 20 are composed may be any suitable materials as stated above in reference to the fabric 10 illustrated in Figs. 1 and 2. Specifically, in fabric 20 the warp is also preferably composed of threads of Bemberg yarn of 100 denier 12 turns per inch, but each thread is of 4-ply yarn. As in the case of fabric 10, a 20 reed is preferably utilized. In the filling there are also 64 picks per inch of 60/2 cotton and of T-9-3 Lastex. However, as illustrated in Fig. 4 the filling arrangement is somewhat different than the filling arrangement of fabric 10. Thus referring to Fig. 4, fabric 20 comprises in the weft in succession two picks of cotton, 1 pick of Lastex (or any other suitable elastic thread) 2 picks of cotton, 1 pick of Lastex, 2 picks of cotton, 1 pick of Lastex and 4 picks of cotton, said last mentioned 4 picks of cotton being arranged in 2 picks each at opposite sides of the same intermediate weft-wise line of crossings of the warp threads. This fabric also has a ribbed appearance in the weft as in the case of fabric 10, but has a less pronounced pile surface or terry effect than fabric 10.

While I have described and illustrated two specific fabric constructions embodying the principles of the present invention, it will be understood that numerous other fabrics embodying the present invention may be produced. Accordingly, I do not wish to be limited precisely to the fabrics herein specifically described, or to either one of said fabrics, or to any other fabric of specific construction, except as may be required by the scope of the appended claims.

Having thus described my invention, what I claim and desire to secure by Letters Patent is:

1. A woven fabric consisting of warp threads and weft threads, said weft threads being arranged in a plurality of groups, said groups being spaced from each other longitudinally of the

fabric, said warp threads being interwoven with said weft threads, all of said warp threads being arranged in groups, each of said groups of warp threads consisting of a plurality of threads, each of said warp threads being crossed by a plurality of others of said warp threads in each of the spaces between adjacent groups of weft threads, the crossing portions of all of said warp threads extending laterally of the fabric in said spaces, and being arranged in groups, said groups of crossing warp thread portions being disposed laterally of each other in the direction of the weft of the fabric, said warp threads being inelastic and at least some of said weft threads in each group being elastic and stretchable and contractible in the fabric.

2. A woven fabric consisting of weft threads and inelastic warp threads, said weft threads being arranged in a plurality of groups, said groups being spaced from each other longitudinally of the fabric, said warp threads being interwoven with said weft threads, all of said warp threads being arranged in groups, each of said groups of warp threads consisting of a plurality of threads, each of said warp threads being crossed by a plurality of others of said warp threads in each of the spaces between adjacent groups of weft threads, the crossing portions of all of said warp threads extending laterally of the fabric in said spaces, and being arranged in groups, said groups of crossing warp thread portions being disposed laterally of each other in the direction of the weft of the fabric, some of said weft threads in each group being elastic and stretchable and contractible in the fabric, and the other of said weft threads being inelastic.

3. A woven fabric consisting of weft threads and inelastic warp threads, said weft threads being arranged in a plurality of groups, said groups being spaced from each other longitudinally of the fabric, said warp threads being interwoven with said weft threads, all of said warp threads being arranged in groups, each of said groups of warp threads consisting of a plurality of threads, each of said warp threads being crossed by a plurality of others of said warp threads in each of the spaces between adjacent groups of weft threads, the crossing portions of all of said warp threads extending laterally of the fabric in said spaces, and being arranged in groups, said groups of crossing warp thread portions being disposed laterally of each other in the direction of the weft of the fabric, some of said weft threads in each group being elastic and stretchable and contractible in the fabric, and the other of said weft threads being inelastic, said inelastic weft threads having a multiplicity of loops therein when said elastic weft threads are in contracted condition in the fabric.

4. A woven fabric consisting of warp threads and weft threads, said weft threads being arranged in a plurality of groups, said groups being spaced from each other longitudinally of the fabric, said warp threads being interwoven with said weft threads, all of said warp threads being arranged in groups, each of said groups of warp

threads consisting of a plurality of threads, each of said warp threads being crossed by a plurality of others of said warp threads in each of the spaces between adjacent groups of weft threads, the crossing portions of all of said warp threads extending laterally of the fabric in said spaces, and being arranged in groups, said groups of crossing warp thread portions being disposed laterally of each other in the direction of the weft of the fabric, said warp threads being inelastic and at least some of said weft threads in each group being elastic and stretchable and contractible in the fabric, said elastic weft threads being partially stretched and under tension in their normally contracted condition in the fabric.

5. A woven fabric consisting of warp threads and weft threads, said weft threads being arranged in a plurality of groups, said groups being spaced from each other longitudinally of the fabric, said warp threads being interwoven with said weft threads, all of said warp threads being arranged in groups, each of said groups of warp threads consisting of a plurality of threads, each of said warp threads being crossed by a plurality of others of said warp threads in each of the spaces between adjacent groups of weft threads, the crossing portions of all of said warp threads extending laterally of the fabric in said spaces, and being arranged in groups, said groups of crossing warp thread portions being disposed laterally of each other in the direction of the weft of the fabric, said warp threads being inelastic and at least some of said weft threads in each group being elastic and stretchable and contractible in the fabric, said groups of crossing portions of said warp threads lying close to each other in the fabric when said elastic weft threads are in contracted condition.

6. A woven fabric consisting of warp threads and weft threads, said weft threads being arranged in a plurality of groups, said groups being spaced from each other longitudinally of the fabric, said warp threads being interwoven with said weft threads, all of said warp threads being arranged in groups, each of said groups of warp threads consisting of a plurality of threads, each of said warp threads being crossed by a plurality of others of said warp threads in each of the spaces between adjacent groups of weft threads, the crossing portions of all of said warp threads extending laterally of the fabric in said spaces, and being arranged in groups, said groups of crossing warp thread portions being disposed laterally of each other in the direction of the weft of the fabric, said warp threads being inelastic and at least some of said weft threads in each group being elastic and stretchable and contractible in the fabric, said elastic weft threads being partially stretched and under tension in their normally contracted condition in the fabric, said groups of crossing portions of said warp threads lying close to each other in the fabric when said elastic weft threads are in contracted condition.

LOUIS DE ROON.
